(57) **CLAIM**

The ornamental design for a tray, as shown and described.

DESCRIPTION

FIG. 1 is a perspective view of a tray showing our new design according to a first embodiment.

FIG. 2 is a left elevation view of the tray of FIG. 1, the right elevation view is a mirror image.

FIG. 3 is a front elevation view of the tray of FIG. 1, the rear elevation view is a mirror image.

FIG. 4 is a top plan view of the tray of FIG. 1.

FIG. 5 is a bottom plan view of the tray of FIG. 1.

FIG. 6 is a plan view of the tray of FIG. 1 in an unfolded configuration.

FIG. 7 is a perspective view of a tray showing our new design according to a second embodiment.

FIG. 8 is a left elevation view of the tray of FIG. 7, the right elevation view is a mirror image.

FIG. 9 is a front elevation view of the tray of FIG. 7, the rear elevation view is a mirror image.

FIG. 10 is a top plan view of the tray of FIG. 7.

FIG. 11 is a bottom plan view of the tray of FIG. 7; and, FIG. 12 is a plan view of the tray of FIG. 7 in an unfolded configuration.

In the drawings, the broken lines show portions of a tray that form no part of the claim.

1 Claim, 12 Drawing Sheets
